(57) **ABSTRACT**

A new and distinct cultivar of New Guinea *Impatiens* plant named 'Ingrosab' characterized by its good branching habit with short internodes, medium sized dark green foliage, large light red-purple flowers with darker spot in the center, and good vigor.

1 Drawing Sheet

1

Latin name of the genus and species of the plant claimed:
Impatiens hawkeri.

Varietal denomination: 'Ingrosab'.

BACKGROUND OF THE NEW PLANT

The present invention comprises a new and distinct New Guinea *Impatiens* plant botanically known as *Impatiens hawkeri* and referred to by the cultivar name 'Ingrosab.'

The new cultivar was developed in a controlled breeding program conducted by the inventor in Enkhuizen, Netherlands. The new New Guinea *Impatiens* cultivar is medium sized with an early flowering response, large flowers with attractive coloration and a good flowering behavior under field conditions.

The new cultivar is propagated from cuttings resulting from the cross in September 2002 of the proprietary New Guinea *Impatiens* selection identified as 'MM 221-1' as female parent and the proprietary New Guinea *Impatiens* selection identified as 'I 203-2' as male parent. 'MM 211-1' is not commercially available and has not patented. 'I 203-2' is not commercially available and has not been patented.

As a result of this cross the present cultivar was selected in September 2003 in Enkhuizen, Netherlands and has been repeatedly asexually reproduced by cuttings in Enkhuizen, Netherlands, in Gilroy, Calif., and in Angers, France over a period of two years. The distinctive characteristics of this new *Impatiens* are stable and reproduced true to type in successive generations of asexual reproduction. It takes 8 to 10 weeks to produce a finished plant, starting from a rooted plug and planted in a 12 cm pot, depending on the temperature.

SUMMARY OF THE INVENTION

The following traits have been repeatedly observed and are determined to be the unique characteristics of 'Ingrosab.' These characteristics in combination distinguish 'Ingrosab' as a new and distinct New Guinea *Impatiens* cultivar:

1. Large, flat, light red-purple flowers with a darker spot in the center
2. Ball shaped plant habit with flowers on top of the foliage
3. Dark green foliage

2

4. Good basal branching character with short internodes
5. Good outdoor vigor

Plants of the new New Guinea *Impatiens* differ primarily from the plants of the female parent selection in the following characteristics:

Plants of the New Guinea *Impatiens* have large light red-purple flowers with darker spot in the center, whereas the plants of the female parent selection have rose flowers.

Plants of the new New Guinea *Impatiens* differ primarily from the plants of the male parent selection in the following characteristics:

Plants of the New Guinea *Impatiens* have large, light red-purple flowers with darker spot in the center, whereas the plants of the male parent selection have light red-purple flowers.

Plants of the new New Guinea *Impatiens* can be compared to plants of 'Fisupnic Lipink,' U.S. Pat. No. 16,118. In side-by-side comparisons conducted in Enkhuizen, Netherlands, plants of the new New Guinea *Impatiens* differed from plants of the cultivar 'Fisupnic Lipink' in the following characteristics:

1. Plants of the new New Guinea *Impatiens* have medium sized leaves, whereas the cultivar 'Fisupnic Lipink' has large leaves.
2. Plants of the new New Guinea *Impatiens* have flat light red-purple flowers with a darker spot in the center, whereas the cultivar 'Fisupnic Lipink' has slightly cup shaped flowers, light red-purple with a larger darker colored spot in the center.

DESCRIPTION OF THE DRAWING

This new New Guinea *Impatiens* plant is illustrated by the accompanying photographic drawing which shows blooms, buds and foliage of the plant in full color, the color showing being as true as can be reasonably obtained by conventional photographic procedures.

DESCRIPTION OF THE NEW CULTIVAR

The following detailed descriptions set forth the distinctive characteristics of this new New Guinea *Impatiens*. The data which defines these characteristics were collected from asexual reproductions carried out in Enkhuizen, Nether-

lands. The plant history was taken on 30 week old plants, blossomed under natural light in the field.

Color readings were taken in the laboratory under ambient light. Color references are primarily to the R.H.S. Colour Chart of The Royal Horticultural Society of London.

The plant:

Classification.—Botanical: *Impatiens hawkeri*.

Parentage:

Female parent.—Proprietary *Impatiens hawkeri* selection identified as code number 'MM 211-1,' not patented.

Male parent.—Proprietary *Impatiens hawkeri* selection identified as code number 'I 203-2,' not patented.

Propagation:

Type cutting.—Terminal cuttings.

Time to initiate roots.—Approximately 7–14 days.

Time to produce a rooted cutting.—Approximately 21 days.

Root description.—Fine, fibrous, and white in color.

Plant description:

General appearance.—Outwardly spreading, low rounded and uniform mounded plant growth.

Habit:

Growth and branching habit.—Freely branching habit, freely flowering, moderate vigorous.

Crop time:

Plant height.—25 cm.

Plant spread.—38 cm.

Lateral branch description:

Length.—12–15.5 cm.

Diameter.—4–7 mm.

Texture.—Smooth, glabrous.

Internode length.—0.6–7 cm.

Color.—RHS 145A to 178A, base to apex.

Foliage description:

Arrangement.—Primarily in whorls.

Length, mature leaves.—8.0 cm.

Width, mature length.—2.9 cm.

Shape.—Lanceolate.

Apex.—Acuminate.

Base.—Acute.

Margin.—Serrulate with fine ciliation.

Texture.—Smooth, slightly rugose.

Venation pattern.—Pinnate.

Color young foliage, upper surfaces.—RHS 146A.

Color young foliage, lower surface.—RHS 146B.

Fully expanded foliage, upper surface.—RHS 147A.

Fully expanded foliage, lower surface.—RHS 147B.

Venation, upper surface.—RHS 147A.

Venation, lower surface.—RHS 187B.

Anthocyanin may be present.—RHS 187C.

Petiole length.—About 1.6 cm.

Petiole diameter.—About 3.0 mm.

Texture.—Smooth, glabrous.

Color.—RHS 178A.

Flower description:

Flower type and flowering habit.—Single.

Number of flowers per leaf axil.—1.

Number of flowers and flower buds per lateral branch.—6.

Flower position.—Above and beyond the foliage and typically facing upwards and outward.

Flower shape.—Rounded, mostly flat.

Flowers lasting.—About 10 days on the plant depending on environmental conditions.

Petals.—Self cleaning.

Gynoecium.—Persistent.

Flowers.—Not fragrant.

Flowering.—Indeterminate and continuous.

Flowering season.—Year round under greenhouse conditions. In the garden, flowering from spring until fall.

Flower length.—About 5.5 cm.

Flower width.—About 5.5 cm.

Flower depth.—About 0.6 cm.

Flower buds:

Bud length.—About 2.2 cm.

Bud diameter.—About 1.1 cm.

Bud shape.—Ellipsoidal.

Texture.—Smooth, glabrous.

Color, just before opening.—RHS 58C.

Petals:

Quantity.—Single, five per flower, imbricate.

Length of banner petal.—About 2.5 cm.

Width of banner petal.—About 3.5 cm.

Length lateral and basal petals.—About 3.2 cm.

Width lateral and basal petals.—About 2.5 cm.

Lateral and basal petal shape.—Cordate.

Banner petal shape.—Cordate.

Petal apex.—Retuse to emarginate.

Petal base.—Attenuate.

Petal margin.—Entire.

Petal texture.—Smooth, satiny.

Petal color.—Upper surface: When opening and fully opened: RHS 62A. Blotch 69C. Lower surface: When opening and fully opened: RHS 61D.

Spur:

Length.—About 4.7 cm.

Texture.—Smooth, glabrous.

Aspect.—Curved.

Color.—RHS 53A.

Peduncles:

Length.—About 5 cm.

Strength.—Strong, flexible.

Diameter.—0.2 cm.

Aspect.—About 45° from the stem.

Color.—RHS 183A.

Reproductive organs:

Androecium.—Stamen number: Five fused at anthers, filaments free, hooded.

Anther shape.—Obovate.

Anther length.—About 5 mm.

Anther color.—RHS 68A to 19D to 151C, base to apex.

Amount of pollen.—Moderate.

Pollen color.—RHS 4D.

Gynoecium:

Pistil number.—One.

Pistil length.—About 3 mm.

Stigma shape.—Columnar, five segmented.

Stigma color.—Colorless.

Style color.—RHS 154C.

Ovary arrangement.—Five celled.

Ovary color.—RHS N144C.

Seed development: Seed development has not been observed.

Disease and pest resistance: Resistance to pathogens and pests common to *Impatiens* has not been observed.

What is claimed is:

1. A new and distinct cultivar of New Guinea *Impatiens* plant named 'Ingrasab', as substantially illustrated and described herein.
